SEWING MACHINE LOOP-TAKER
MECHANISM

Walter Myers, Bridgeport, Conn., assignor to The
Singer Manufacturing Company, Elizabeth,
N. J., a corporation of New Jersey

Original application April 16, 1936, Serial No.
74,615. Divided and this application January
19, 1937, Serial No. 121,251

7 Claims. (Cl. 112—184)

This invention relates to improvements in
stitch-forming mechanisms for sewing machines
and has for its primary object to provide sup-
porting and actuating means for a sewing ma-
chine loop-taker, more specifically of the vertical-
axis rotary hook type, which is particularly
adapted for high speed operation.

With the above and other objects in view, as
will hereinafter appear, the invention comprises
the devices, combinations and arrangements of
parts of a loop-taker actuating mechanism de-
scribed in connection with the accompanying
drawings which illustrate a preferred embodi-
ment of the invention and in which:

15 Fig. 1 represents a vertical longitudinal sec-
tion, partly in front elevation, of a sewing ma-
chine containing the present improvement. Fig.
2 is a bottom plan view of the machine. Fig. 3
represents an enlarged transverse section of the
bed-plate, substantially on the line 3—3 of Fig.
2. Fig. 4 represents a perspective view, partly in
section, of one of the rotary-hook brackets, in-
cluding a portion of the rotary hook mechanism
thereof. Fig. 5 is a top-plan, partly in section,
of the adjacent rotary hook brackets. Fig. 6
represents a section of one of the rotary-hook
brackets, in substantially a plane containing the
vertical axis of the hook-shaft. Fig. 7 repre-
sents a horizontal section of the hook-bracket,
substantially on the line 7—7 of Fig. 6.

As described in my co-pending patent applica-
tion, Serial No. 74,615, filed April 16, 1936, of
which this application is a division, and as il-
lustrated in the accompanying drawings, the
35 present invention has been embodied in a sew-
ing machine having a frame comprising a work-
supporting bed-plate 1 provided with left and
right slide-plates 2 and 3 and with a throat-plate
4 between said slide-plates. Rising from one end
40 of the bed-plate 1 is the hollow standard 5 of a
tubular bracket-arm 6, which overhangs the bed-
plate and terminates at its free end in a head 7.

Extending longitudinally of and disposed with-
in the bracket-arm 6 is a horizontally disposed
45 rotary main-shaft 8, one end of said shaft car-
rying a belt-pulley 9 and being journaled in a
ball-bearing 10 disposed within a bearing-boss
11 projecting from the bracket-arm 6. The main
shaft 8 is also journaled in a bearing bushing
50 12 and, at its end adjacent said bushing, car-
ries a crank 13 connected by the usual link 14
with a needle-bar 15 carrying at its lower end
a pair of needles 16 arranged abreast with re-
spect to the direction of feed of the work.

55 The needle-bar 15 is journaled for vertical re-

ciprocation in a pendulous frame 17 pivotally
hung upon a taper-headed fulcrum-pin 18 for
swinging movements within the head 7 about an
axis substantially parallel to the axis of rotation
of the main-shaft 8, said fulcrum-pin being se-
cured by a screw 18' threaded into the head 7.

Disposed below and adjacent the rearward
edge of the bed-plate 1, substantially parallel to
the main-shaft 8, is a loop-taker and feed-actu-
ating shaft 19. Adjacent one end thereof, the
shaft 19 is journaled in a ball-bearing 20 sus-
tained by a bearing-lug 21 depending from the
bed-plate 1. At its opposite end, the shaft 19 is
journaled in a bearing-bushing 22 secured in a
lug 23 depending from the bed-plate 1, and in-
termediate its ends the shaft 19 is journaled in
another bearing-bushing 24 secured in a lug 25
depending from said bed-plate. The bushings 22
and 24 are extended to project toward each other
from proximate faces of the bearing-lugs 23 and
25. At its free end, adjacent to the ball-bearing
20, the shaft 19 carries a peripherally grooved
belt-pulley 26 connected by a clip-belt 27 with
a similar pulley 28, of the same size as said pul-
ley 26 and carried by the main-shaft 8, whereby
the shaft 19 is driven at the same speed as said
main-shaft 8.

Carried by the shaft 19, between the proximate
ends of the bearing-bushings 22 and 24, are two
spiral-gears 29 and 30 in driving engagement
with spiral-gears 31 and 32, respectively, the gear
ratios being such that the driven gears 31, 32
are rotated at twice the speed of the driving gears
29, 30. The driven gears 31, 32 are carried by
vertically disposed loop-taker shafts 33, 34, re-
spectively, said shafts being of similar construc-
tion and each carrying at its upper end a loop-
taker 35, or 36, of the vertical-axis rotary hook-
type. These loop-takers cooperate with the nee-
dles 16 in the formation of lock-stitches; the
needle-thread loops seized by the loop-takers be-
ing each cast about a lower thread mass con-
tained in a bobbin-case 37, journaled in the re-
spective loop-taker and restrained against rota-
tion therewith by a suitable stop-notch 38 at the
under side of the throat-plate 4.

The loop-taker shaft 33 is journaled in ver-
tically spaced bearing-lugs 39 and 40 projecting
from a left-hand loop-taker bracket 41, said
bracket 41 having at its rearward end a split
bearing-boss 42 adjustably clamped upon the
bushing 22 by a screw 43. At its forward end,
the bracket 41 is provided with a foot 44 having
a rounded upper face secured by a screw 45
against a seat afforded by the horizontally flat-

tened lower end of a lug 46 depending from the bed-plate 1. The bracket-securing screw 45 passes through a slot 47 provided in the foot 44, said slot being elongated in a direction to 5 provide for adjustment of the bracket 41 toward and from the path of needle reciprocation.

The loop-taker shaft 34 is likewise journaled in vertically spaced bearing-lugs 48 and 49 projecting from a right-hand loop-taker bracket 10 50, said bracket 50 having at its rearward end a split bearing-boss 51 adjustably clamped by a screw 52 upon the bushing 24. At its forward end, the bracket 50 is provided with a foot 53 having an elongated slot 54 entered by a screw 15 55 which secures the foot 53 against a horizontal seat 56 formed by suitably recessing a lug 57 depending from the bed-plate 1.

The loop-taker shafts 33 and 34 are similarly journaled in the brackets 41, 50. Referring more 20 particularly to Figs. 6 and 7 of the drawings, the upper bearing-lug 48 of the bracket 50 has a vertical aperture 48'. Threaded into said aperture from the under side thereof is a bushing 153 secured in set position by a screw 154. The 25 bushing 153 provides a seat for and serves to vertically locate an outer race-ring 58, which is preferably force-fitted to its seat and is thereby restrained against rotation. An inner race-ring 59 closely embraces the shaft 34 and is preferably 30 caused to rotate with said shaft by a clutch-ball 60 disposed within said race-ring 59 and in a recess 61 peripherally provided in the shaft 34. The base of the recess 61 is preferably a plane surface and is formed so that the depth of 35 said recess, medianly of its length, is preferably substantially equal to the diameter of the ball 60, to provide for assemblage of the parts. Upon rotation of the shaft 34, the ball 60 will instantly grip the inner race-ring 59 and will induce 40 rotation with the shaft of the inner race-ring. This arrangement facilitates securing the inner race-ring to its shaft and obviates the distortion of the parts likely to occur by employment of ring-securing screws. A series of 45 bearing-balls 62 is interposed between the race-rings 58 and 59 in the usual manner to complete the upper ball-bearing of the loop-taker shaft 34.

Resting upon the inner race-ring 59 is an oil-guard washer 63 which is undercut to overhang 50 the outer race-ring 58 in spaced relation thereto, thereby providing a clearance-recess 64 above said race-rings for supplying lubricant to the bearing-balls 62. The washer 63 is held in place by an eccentric 65 formed or otherwise provided 55 upon the shaft 34 directly below the loop-taker 36, said washer serving to guard against emission of lubricant from the upper end of the bearing-lug aperture 48'.

The eccentric 65 is embraced by the strap 60 of a short pitman 66 pivotally connected by a stud-bolt 67 to a horizontally vibratory arm 68 of an angular opener-carrier 68, 69. The arm 68 of the carrier is disposed in a suitably shaped cavity 70 provided in the upper face of the 65 bracket 50, one end of said arm 68 being pivotally secured by a fulcrum-stud 71 fixed in the bracket 50 by a set-screw 72. The vertically disposed arm 69 of the opener-carrier extends above the bracket 50 and is horizontally grooved 70 in its upper end to provide a seat for the shank of the usual opener-finger 73 adapted to engage intermittently and oscillate the bobbin-case 37, thereby to open a thread-passage in the bobbin-case rotation restraining means. The shank of 75 the finger 73 is slotted to receive a finger-secur-

ing screw 74 and to provide for adjustment of said finger.

The lower end of the loop-taker shaft 34 is journaled in an aperture 49' provided in the bearing-lug 49, said aperture 49' being in vertical alinement with the upper lug aperture 48'. Similarly to the upper ball-bearing, the lower ball-bearing includes a series of balls 75 disposed between a fixed outer race-ring 76 and an inner race-ring 77, the inner race-ring 77 embracing and being caused to rotate with the shaft 34 by a clutch-ball 78 disposed in a recess 79 peripherally provided in said shaft. The outer race-ring is vertically located by a bushing 155 threaded into the lower lug from the under side thereof, said bushing being secured in set position by a screw 156. Overlying the lower ball-bearing is an undercut oil-guard washer 80 similar to the upper-bearing washer 63 and defining a clearance-recess 81 above the ball-bearing for supplying lubricant to the bearing-balls 75. The washer 80 is held in place by the hub of the driven gear 32, disposed between the bracket-lugs 48, 49 and secured to the shaft 34 by a set-screw 82.

The journaling of the loop-taker shaft 33 in the bearing-lugs 39, 40 of the bracket 41 and the bobbin-case opener mechanism actuated by said shaft 33 correspond in detail with the described journaling of the shaft 34 and its bobbin-case opener mechanism. Accordingly, the parts have been correspondingly designated in the drawings, so far as illustrated in detail.

Lubricant is supplied to the bearings of the loop-taker shafts from reservoirs carried by the 35 respective loop-taker brackets and connected by separate conduits with the shaft bearings. Referring more particularly to Figs. 4 and 5 of the drawings, the bracket 41, for example, is preferably integrally provided with a trapezoidal lubricant-supply reservoir 83 disposed adjacent to the opener-mechanism cavity 70 in said bracket. The rearward portion of the reservoir 83 is closed at the top by an overhanging roof-wall 83', which is preferably integral with the side walls of the 40 reservoir and terminates short of the forward wall, thereby to provide a top opening 84 in the forward portion of the reservoir. The roof-wall 83' functions to retain lubricant within the reservoir 83 when the sewing machine is tilted back 45 for access to the mechanism below the bed-plate 1. Preferably, a lubricant-absorbent pad 85 is placed upon the bottom of the reservoir 83 to control the flow of lubricant therefrom.

The bottom of the reservoir 83 has an aperture 86 opening into an oil duct 87 provided in the bracket 41 below and extending horizontally crosswise of the front end of said reservoir. The outer end of the duct 87 is sealed by a plug 88 and its inner end is connected with a horizontal 60 duct 89, provided in the bracket-bearing lug 39 and extending transversely of the duct 87. The outer end of the connecting duct 89 is sealed by a plug 90 and its inner end terminates in a reduced bore 89' communicating with the clearance-recess 64 above the shaft-bearing balls 62.

The bottom of the reservoir 83 has another aperture constituting the upper end of a vertical duct 91 provided in the bracket 41. The lower end of said duct 91 opens into a horizontally-transverse bracket-duct 92 closed at its outer end by a plug 93. At its inner end, the duct 92 has a restricted bore 94 in the bracket-lug 40, said bore 94 communicating with the clearance-recess 61 above the shaft-bearing balls 75.

5 In the sewing machine illustrated in the accompanying drawings, the work is intermittently advanced past the stitch-forming mechanism by a so-called compound feeding mechanism including a lower or drop-feed and a needle-feed. This feeding mechanism is fully disclosed in my prior patent application Serial No. 74,615 hereinbefore referred to and, as the present invention is not limited to any specific form of feeding mechanism, it is deemed unessential to describe 10 the same.

Having thus set forth the nature of the invention what I claim herein is:—

15 1. Loop-taker mechanism for sewing machines, comprising, a supporting bracket having vertically spaced bearing-lugs, a vertically disposed loop-taker carrying shaft, ball-bearings in said lugs providing vertically spaced journals for said shaft, driving connections for rotating said shaft, a lubricant-supply reservoir in said bracket adjacent to and connected with the upper of said ball-bearings, and means for conducting lubricant from said reservoir to the lower of said ball-bearings.

20 25 2. Loop-taker mechanism for sewing machines, comprising, a supporting bracket having vertically spaced bearing-lugs, a vertically disposed loop-taker carrying shaft, ball-bearings in said lugs providing vertically spaced journals for said shaft, driving connections for rotating said shaft, a lubricant-supply reservoir upon said bracket having a roof wall closing the upper rearward portion of the reservoir and leaving the front portion of said reservoir open at the top, and means for conducting lubricant from said reservoir to said ball-bearings.

30 35 3. Loop-taker mechanism for sewing machines, comprising, a supporting bracket having vertically spaced bearing-lugs provided with vertically aligned apertures, a vertically disposed loop-taker carrying shaft peripherally provided with vertically spaced recesses, ball-bearings disposed in the apertures of said lugs and providing vertically spaced journals for said shaft, said ball-bearings including outer race-rings fixed in the 40 45 respective bearing-lugs and inner race-rings embracing said shaft recesses, clutch-balls disposed in said shaft recesses for effecting rotation of

said inner race-rings with said shaft, and driving connections for rotating said shaft.

4. Loop-taker mechanism for sewing machines, comprising, a supporting bracket having vertically spaced bearing-lugs provided with vertically aligned apertures, bushings threaded into said lugs, a vertically disposed loop-taker carrying shaft, ball-bearings disposed in the apertures of said lugs and providing vertically spaced journals for said shaft, said ball-bearings including outer race-rings engaged and vertically located by said bushings, means for securing said bushings, and driving connections for rotating said shaft.

5. Loop-taker mechanism for sewing machines, comprising, a supporting bracket having vertically spaced bearing-lugs provided with vertically aligned apertures, a vertically disposed loop-taker carrying shaft, ball-bearings disposed in the apertures of said lugs and providing vertically spaced journals for said shaft, means including a bushing threaded into one of said lugs for locating said ball-bearings in vertically spaced relationship, and driving connections for rotating said shaft.

15 20 25 6. Loop-taker mechanism for sewing machines, comprising, a supporting bracket having vertically spaced bearing-lugs provided with vertically aligned apertures, a vertically disposed loop-taker carrying shaft, ball-bearings disposed in the apertures of said lugs and providing vertically spaced journals for said shaft, bushings disposed in said bearing-lug apertures below and in engagement with said ball-bearings, and driving connections for rotating said shaft.

30 35 40 45 7. Loop-taker mechanism for sewing machines, comprising, a supporting bracket having vertically spaced bearing-lugs provided with vertically aligned apertures, a vertically disposed loop-taker carrying shaft, ball-bearings disposed in the apertures of said lugs and providing vertically spaced journals for said shaft, a bushing disposed in one of said bearing-lug apertures and providing a positioning shoulder for one of said ball-bearings, and driving connections for rotating said shaft.

WALTER MYERS.
